UNITED STATES PATENT OFFICE.

WILLIAM C. BUCHANAN, OF BELLEVILLE, ILLINOIS, ASSIGNOR TO THE HARRISON MACHINE WORKS, OF SAME PLACE.

COMBINED STRAW CARRIER AND STACKER.

SPECIFICATION forming part of Letters Patent No. 367,182, dated July 26, 1887.

Application filed September 8, 1886. Serial No. 212,999. (No model.)

To all whom it may concern:

Be it known that I, WILLIAM C. BUCHANAN, of Belleville, in the county of St. Clair and State of Illinois, have invented a new and Improved Combined Straw Carrier and Stack 5 and, of which the following is a full, clear, and exact description.

The object of my invention is to provide a new and improved combined straw carrier and stacker which permits of being easily and quickly adjusted on uneven ground, and is simple and durable in construction and very effective in operation.

The invention consists of various parts and combinations of the same, as will be fully described hereinafter, and pointed out in the claims.

Reference is to be had to the accompanying drawings, forming a part of this specification, in which similar letters of reference indicate corresponding parts in all the figures.

Figure 1 is a side elevation of my improvement connected with the rear part of a thrashing-machine. Fig. 2 is a broken side elevation of the carriage carrying the stacker. Fig. 3 is a plan view of the leveling-frame. Fig. 4 is a vertical cross-section of the carriage on the line *xx* of Fig. 2. Fig. 5 is a plan view of the rear part of the thrashing-machine and part of the carrier. Fig. 6 is a detail plan view of the stacker-supporting ropes. Fig. 7 is a sectional elevation of the upper end of the carrier. Fig. 8 is a plan view of the same. Fig. 9 is a side elevation showing my improved carrier and stacker folded up ready for transportation.

The carriage A is provided with the frame B, mounted on the wheels C, placed at about one-third the length of the frame B from the rear end, which is provided with the supporting-bars B', which support the stacker when folded up for transportation, as shown in Fig. 9.

To the front of the frame B is secured in the middle the tongue B', and on each side is placed a leg, D, having the slot D', through which passes a bolt, E, fastened to the frame B, and on which screws the nut E'.

On each side of the frame B, between the legs D and the wheels C, is secured a bracket,

F, on which swings the leveling-frame G, provided on its front at each corner with a bolt, H, passing through a slotted leg, H', supported at its lower end by the bolt E in the frame B. On the bolts H screw the handled nuts, H², which, when screwed up, serve to hold the leveling-frame G in adjusted position. 55

On the top of the frame G is placed the circular track G', on which travels the stacker base or frame I, consisting of the arm or beam I' and the radial arm I², both resting with their outer ends on the track G'. 60

On each outer end of the arm or beam I' is secured the box J and the bracket J', as seen in Figs. 3, 4, respectively, on which are pivoted the brackets or arms K, attached with their upper ends to the lower end of the stacker L. 65

On the bottom of the leveling-frame G is mounted the shaft M, carrying on its outer end the sprocket-wheel M', and on its inner end the beveled gear-wheel M², which meshes into the beveled gear-wheel M³, secured to a vertical shaft, M⁴, which has its bearings in the frame B, and also forms the center pivot 70 for the stacker base or frame I.

To the upper end of the shaft M⁴ is attached the beveled gear-wheel M⁵, meshing into the beveled gear-wheel M⁶, secured to the horizontal shaft M⁷, having its bearings in the boxes J and J², secured to the beam I. To the outer end of the shaft M⁷ is fastened a sprocket-wheel, M⁸, over which passes the endless sprocket-chain M⁹, which also passes over the sprocket-wheel M¹⁰, attached to the shaft N, mounted 85 in the lower end of the stacker L and carrying the pulleys N', over which pass the endless belts N², carrying the stacker-slats N³, and also passing over similar pulleys, N⁴, mounted in the upper end of the stacker. 90

From each end of the beam I' of the stacker-frame I projects a pin, I³, which comes in contact with the stop-plate I⁴, secured to the leveling-frame G when frame I is swung at right angles, thus preventing a complete turning of 95 the stacker-frame as it is turned on the shaft M⁴. One of the side beams of the frame G is extended in front and carries on its outer end a supporting and guiding sprocket-wheel, O, over which passes the upper parts of the 100

sprocket-chain O' , which also passes over the wheel M' on the frame G and over the sprocket-wheel O' , secured to the shaft O' , mounted on the rear part of the thrashing-machine P , 5 and receiving a rotary motion from a suitable revolving shaft on the thrashing-machine.

On the shaft O' is mounted, to swing, the folding carrier Q , provided with the usual slat-belt, Q' , which passes over suitable pulleys on the shaft O' and over similar pulleys on the shaft Q' , which is provided on one outer end with the pulley Q^3 , which connects by the twisted belt Q^4 with the pulley Q^5 , secured to the shaft Q^6 , which extends across the upper 15 end of the carrier Q and carries a fan-wheel formed of two or more radial arms or fan-plates, Q^7 , which, when rotating, force the straw from the upper end of the slat-belt downwardly upon the slat-belt N^2 of the stacker L . Two deflecting-bars, Q^8 , extend diagonally across the slat-belt Q' on top, near the discharge-opening Q^9 , and serve to guide the straw toward the center of the opening Q^9 . (See Fig. 8.)

The carrier Q is supported on each side by 25 a rope, R , which passes upward and over a pulley, R' , mounted on the arm R^2 , projecting from the rear end of the thrasher P and supported on the top of the same. Each rope R then runs to a windlass, R^3 , attached to the 30 arm R^2 . The latter is supported by a brace, R^4 , attached to the thrasher P .

Near the upper ends of the side arms, R^2 , is pivoted the boom S , supported on its upper end by the chain S' , secured with one end to the top of the thrasher P .

On the boom S is also hung a pulley, S^2 , over which passes a rope, S^3 , attached with its inner end to the windlass S^4 , mounted on the upright post P' of the thrasher P . To the other end 40 of the rope S^3 is secured a pulley, S^5 , over which passes a rope, S^6 , attached with its ends to a bar, S^7 , carrying on each outer end a pulley, S^8 , over which passes a rope, S^9 , fastened with its ends to the side of the stacker L , near its 45 upper end.

The operation is as follows: When the stacker is placed in the position shown in Fig. 1, then the pulley S^2 is perpendicular above the center of the stacker-carriage frame I , so that the 50 stacker L can be swung to any desired angle with the thrashing-machine P , turning with its frame I on the track G' of the leveling-frame G , the shaft M^4 being the center. The frame G is placed on a level by adjusting the 55 legs H' to the desired height, and the frame B is held in position by adjusting the legs D on the bolts E , and fastening them in the desired place by the nuts E' . It is not necessary that the frame B should be in a horizontal position, 60 as it may be set on the side of a hill, the length of the machine being disposed transversely to the irregularity or slope. The slat-belt N^2 of the stacker L is operated simultaneously with the slat-belt Q' of the carrier Q by rotating the 65 shaft O' , in any suitable manner, from a revolving shaft of the thrashing-machine P . The rotation of the shaft O' and slat-belt Q' ele-

vates the straw in the carrier Q until it reaches the opening Q^9 in the upper part of the carrier, and then the straw is forced downward upon the stacker L by the action of the fan-wheel Q^7 , rotated by the belt Q^4 from the shaft O' . The rotary motion of the shaft O' is transmitted to the shaft M by the chain O' and the sprocket-wheels O^2 and M' , and the motion of 75 the shaft M is transmitted to the shaft N of the stacker L by the gear wheels and shafts M^2 , M^3 , M^4 , M^5 , and M^6 and the sprocket-wheels M^8 and M^9 and chain M^9 . The shaft N operates the slat-belt N^2 , and thereby ele- 80 vates the straw in the stacker L .

It will be seen that the stacker L can, when the machine is in motion, be swung in any direction by turning the same on its base I , and it can be raised or lowered by swinging on the 85 pivoted brackets K and turning the windlass S^4 , which by its rope S^3 is connected with the upper end of the stacker L .

The tongue B^2 is generally attached to the rear part of the thrashing-machine; but the 90 stacker L can also be transported independently of the thrasher P by disconnecting the ropes S^3 and the belt O' . The several parts of the carrier can be folded up and rested against the thrashing-machine, and the stacker L can 95 be folded up and rested on the bars B' of the frame B , as shown in Fig. 9.

Having thus fully described my invention, what I claim as new, and desire to secure by Letters Patent, is—

100

1. The combination of the carrier provided with the fan-wheel Q^7 in its upper end, with a stacker and a leveling-frame, substantially as shown and described.

2. The combination of the carrier Q , provided with the fan-wheel Q^7 , with the stacker L , a leveling-frame, G , and the stacker-carriage B , on which the said leveling-frame G is pivoted, substantially as shown and described.

3. The stacker-frame B , the wheels C , and the frame G , in combination with the legs D and legs H' , each having slots, bolts H and E , and handled nuts E' and H^2 , respectively adapted to clamp together the frames B and G and the legs D and H' , substantially as and 110 for the purpose set forth.

4. The stacker-frame B , provided with the brackets F , in combination with the adjustable leveling-frame G , pivoted on the said brackets F , substantially as shown and de- 115 scribed.

5. The stacker-frame B , provided with the brackets F , in combination with the leveling-frame G , pivoted on the said brackets F , and the adjustable legs H' , supporting the frame 125 G , substantially as shown and described.

6. The straw-carrier Q , provided with the slat-belt Q' and the fan-wheel Q^7 , in combination with the deflecting-bars Q^8 , substantially as shown and described.
